UNITED STATES PATENT OFFICE.

ROBERT STICKDORN, OF DUSSELDORF, GERMANY.

FLUSHING APPARATUS FOR WATER-CLOSETS.

985,952.

Specification of Letters Patent.

Patented Mar. 7, 1911.

Application filed August 19, 1909. Serial No. 513,573.

To all whom it may concern:

Be it known that I, ROBERT STICKDORN, a citizen of the German Empire, residing at Dusseldorf, Germany, have invented new and useful Improvements in Flushing Apparatus for Water-Closets, of which the following is a specification.

The special feature of the new distributing mechanism consists in the arrangement 10 of an automatic valve closing-member in the water-inlet socket, being at a right angle relative to the main valve-box, in the provision of special mechanical motive means for same, further in its being shaped for 15 shutting up the box in either sense and besides in the placing of the inlet socket below the connecting arm intermediate the flushing-box and the distributing case.

In the accompanying drawing: Figure 1 20 is a perspective view of my improved flushing apparatus, showing it applied to a water closet; Fig. 2 a vertical section through the valve, and Figs. 3 and 4 are similar sections showing the parts in different positions.

Within a valve casing *b*, is axially movable a valve plug comprising two piston-like closing members *h*, and *v*, the diameter of member *h* exceeding that of member *v*, so as to constitute a differential piston. Members *h*, *v* are separated by a recessed plug-section *a*, and a coniform section *k*, the maximum diameter of cone *k* corresponding substantially to that of member *h*. Casing *b*, is provided with a water inlet nozzle or 35 socket *w'*, to which a water supply pipe *w* is coupled. Above socket *w'* there opens into casing *b*, a pipe *d* connecting an air chamber with said casing. Nozzle *w'* is provided with a pair of valve seats *s* and *t*, 40 adapted to be engaged by a disk-valve *o*, the axis of which extends at right angles to that of piston *h*, *v* and which is provided toward either side with stopping-up faces and guided by means of ridges *r*. This is 45 equipped with a chamfered knob or abutment *z* which, when the valve-disk has moved itself in the direction of the distributing case, so as to rest on the valve-seat *s*, projects into the distributing case and is 50 consequently adapted to be acted upon by the distributing body and to effect the same in turn.

The cycle of operations with the distributing mechanism is as follows:—When the 55 distributing body is in the lifted position,

as shown in Fig. 2, the discharge from the air chamber *g* toward the down-pipe is free, as in this case the water can flow along by the side of the cone *k* and of the closing member, passing then through the cylindrical part *b'* of the casing to the outlet leading to the bowl. On the other hand the water inlet is shut up, the pressure of the water forcing the closing member *o* against the seat *s*. If now, however, the distributing body is pressed down by means of a pressure on the handle *c* of same, first the piston-like closing member *v* is moved in the cylindrical part of the case shutting this up. When the distributing body moves 70 down farther, the cone *k* strikes against the knob *z*, thereby pressing back the valve-disk *o* from the seat *s*, so as to allow the water to flow in and to enter into the air-chamber *g*. As soon as the distributing body has been 75 completely pressed down, the knob *z*, owing to the pressure of the water, passes over the cone-rim or shoulder *k'*, chamfered away or slanted at the top, thereby retaining the distributing body in its position, as 80 shown in Fig. 3. When now the cistern is filled and the same tension is obtained in this as well as in the piping, the distributing body is lifted, the prevailing water-pressure being able to exert in the well known manner on the piston-like part *h*, having the larger diameter, a greater force than on the body *v*. During this operation the valve-disk *o* is slightly pressed back, due to the 85 chamfering away or slanting of the pivot *z*, and in given cases owing to the projecting rim of the cone; this takes place without resistance due to the equalization of the pressure in front of and behind the valve-disk *o*. If now the cone has been lifted the distance 90 sufficient, so that the valve-disk gets its position opposite the cylindrical part below same, as shown in Fig. 4, the valve-disk is free to move back to the seat *s* so as to close the influx of water. But all the same and 95 due to the pressure prevailing in the air chamber *g*, the distributing body is lifted farther, that is, till the upper face of the closing member *v* strikes against the knob *z*, which prevents it from continuing its upward movement. The closing-member *v* finally leaves the narrower part *b'* of the case, as illustrated in Fig. 2, so that, after 100 the opening of the valve *v*, the water of the air chamber *g* flows to the basin of the 105 110

closet, causing it to be flushed. When pressing down again the distributing body, the same operation repeats itself.

In order to prevent the contents of the closet bowl from being drawn by suction into the water supply pipe through branch *w* whenever a reduction of pressure in said pipe should take place, piston *h*, *k* is made hollow, its interior communicating through ports *c'* with the atmosphere. Thus when the parts are in their inoperative position (Fig. 2), the interior of casing *b* communicates with the open air through ports *c'*. As soon as a reduction of pressure occurs in the water supply pipe, disk *o* will be drawn against seat *t* to close branch *w*. If casing *b* would not communicate with the atmosphere, suction would be created therein whenever a reduction of pressure in the water supply pipe should occur, which suction would draw the contents of the bowl into casing *b* and branch *w*.

I claim:

1. In a flushing apparatus for water closets, an air chamber, a casing communicating therewith, a water inlet, a water outlet, a differential piston within the casing and controlling communication between the casing and said outlet, a separate valve controlling communication between the inlet and the casing, and an abutment on the valve which is adapted to be engaged by the piston.
2. In a flushing apparatus for water closets, an air chamber, a casing communicating therewith, a differential piston inclosed within the casing, a cone on said piston, a water inlet, a valve controlling communication between said inlet and casing, and an abutment on the valve which is adapted to be engaged by the cone.
3. In a flushing apparatus for water

closets, an air chamber, a casing communicating therewith, a differential piston inclosed within the casing, a cone on said piston and having a shoulder, a water inlet, a valve controlling communication between said inlet and casing, and an abutment on the valve which is adapted to be engaged by said cone and shoulder.

4. In a flushing apparatus for water closets, an air chamber, a casing communicating therewith, a differential piston inclosed within the casing, a cone on said piston, a water inlet, a valve controlling communication between said inlet and casing, the axis of said valve extending at right angles to that of the piston, and an abutment on the valve which is adapted to be engaged by the cone.

5. In a flushing apparatus for water closets, an air chamber, a casing, a pipe connecting said chamber to the casing, a differential piston inclosed within the casing and having a coniform section, a water inlet nozzle entering the casing below the pipe, and a valve controlling said nozzle and having an abutment that is adapted to engage the coniform piston-section.

6. In a flushing apparatus for water closets, a valve casing, an air chamber communicating therewith, a differential piston inclosed within the valve casing, a water inlet nozzle having a pair of opposed valve seats, a disk valve intermediate said seats, and an abutment on said valve which is adapted to be engaged by the piston.

Signed by me at Cologne, Germany, this 7th day of August 1909.

ROBERT STICKDORN.
